Baldwin Wright

UNITED STATES PATENT OFFICE.

GEORGE HENRY FORRESTER, OF IVER, ENGLAND.

CONCRETE WALL.

1,379,754.

Specification of Letters Patent.

Patented May 31, 1921.

Application filed October 5, 1920. Serial No. 414,792.

To all whom it may concern:

Be it known that I, GEORGE HENRY FORRESTER, a subject of the King of Great Britain, residing at "Riemore," Iver, in the 5 county of Buckingham, England, have invented a new and useful Improvement in Concrete Walls, of which the following is a specification.

This invention relates to devices especially 10 applicable for use with hollow walls of concrete and the like and to means for reinforcing such walls.

According to this invention a device for use in the construction of walls consists of a 15 tube which may be of concrete or cement having a bar projecting from each side.

In the case of a hollow wall, sets of two tubes are placed in alinement, one in each 20 part of the wall, each tube being of a length corresponding to the width of each of the parts of wall respectively. The plates or 25 boards which form the molds for the walls are tied together by rods which pass through the tubes which form distance pieces between the outer and the inner plates or 30 boards. After the concrete of which the walls are formed has set, the rods and the plates or boards are removed and screw bolts are inserted into the tubes passing through holes in the bars projecting from them and secured by means of nuts which engage with the bars. Ties securing the two walls together are thus formed.

Single walls may be made in a similar 35 manner.

In all cases holes may be made in the parts of the bars which project from the tubes and adjacent tubes are connected together by horizontal reinforcing bars, while 40 vertical reinforcing bars are inserted through the holes.

The accompanying drawing illustrates a hollow wall made in accordance with this invention. Figure 1 is a horizontal section of 45 a finished wall and Fig. 2 is a similar view of the wall in course of erection with the mold plates in position. Fig. 3 is a transverse vertical section of the wall in course of erection and Fig. 4 is a longitudinal vertical 50 section. Fig. 5 is a perspective view of a partly finished wall.

Referring more particularly to Figs. 2 and 3, two sets of mold plates *a* are erected, the outer plates, to which are attached corrugated plates, being secured together by 55 wooden bars *b* and rods *c* which pass

through tubes *d*, the rods *c* being secured by nuts *e*. The tubes *d* form the distance pieces between the inner and outer plates *a*, forming the mold for the two walls, and distance 60 pieces *f* are inserted between the inner plates so that a space is left between the walls. Bars *g* extend from each side of the tubes *d* and the bars *g* of adjacent tubes *d* are connected together by horizontal reinforcing bars *j* 65 and vertical reinforcing bars *k* pass through holes in the bars *g*.

After the mold plates have been erected concrete is poured in and when it is set the mold plates *a* are removed and screw bolts 70 *l* (Fig. 1) are inserted into the tubes *d* passing through holes in the bars *g*. The screw bolts *l* are secured by nuts *m* which engage with the bars *g*, as shown in Fig. 1.

Referring to Fig. 5, it will be seen that the 75 mold plates of the upper part have been removed but that they are still in position on the lower part. The walls *j*, *j*, having an air space between them and the window frames in position can be clearly seen. 80

What I claim is:—

1. A device for use in constructing walls of concrete and the like consisting of a tube and a bar extending transversely through the tube having arms on opposite sides and 85 a bolt receiving hole within the tube, one of said arms being provided outside the tube with a bar receiving hole.

2. The combination of a ferro concrete 90 wall, with a tube having a bar passing transversely through the middle point of its longitudinal axis and projecting from each side thereof, and having holes in the projecting parts adapted to receive reinforcing bars.

3. The combination of a ferro concrete 95 wall, with a tube having a bar passing transversely through the middle point of its longitudinal axis and projecting from each side thereof and having two holes in each projecting part, one hole adapted to receive 100 a vertical reinforcing bar and the other to receive a horizontal reinforcing bar.

4. In combination with a hollow wall, two tubes each having a bar projecting from each side and placed in alinement one in 105 each part of the wall and a screw bolt passing through the tubes secured by a nut which engages with the bar.

5. In combination with a hollow wall, two tubes each having a bar projecting from each side and placed in alinement one in 110 each part of the wall, a screw bolt passing

through the tubes secured by a nut which engages with the bar and horizontal reinforcing bars secured to the bars projecting from adjacent tubes.

- 5 6. In combination with a hollow wall, two tubes each having a bar projecting from each side and placed in alinement one in each part of the wall, a screw bolt passing through the tubes secured by a nut which engages with the bar and vertical reinforcing bars passing through holes in the bars projecting from the tubes.
- 10 7. In combination with a hollow wall, two

tubes each having a bar projecting from each side and placed in alinement one in each part of the wall, a screw bolt passing through the tubes secured by a nut which engages with the bar, horizontal reinforcing bars secured to the bars projecting from adjacent tubes, and vertical reinforcing bars 20 passing through holes in the bars projecting from the tubes.

In testimony that I claim the foregoing as my invention I have signed my name this 17th day of August, 1920.

GEORGE HENRY FORRESTER.
